APPARATUS FOR MAKING OPEN-HEARTH STEEL

Martin J. Conway, Coatesville, Pa.

Application June 20, 1934, Serial No. 731,456

12 Claims. (Cl. 263—15)

This invention relates to the manufacture of steel or products requiring a similar heat treatment and more particularly to an improved method and apparatus for manufacturing what is known as open-hearth steel and is a continuation in part of the invention disclosed in an application filed under Serial No. 628,172 for Open-hearth furnace by the present inventor on August 10, 1932.

5 Prior to this invention open-hearth steel has always been made in what is known as a reversing type of open-hearth furnace. In accordance with this previous practice the materials, comprising scrap, pig iron, molten iron, limestone, etc., from which the steel is produced, are placed on an open hearth in a covered furnace, usually of rectangular shape, and burning gases which develop most of the heat for the chemical reactions are passed over them, first from one end of 10 the furnace and then from the other, through ports located in each end of the furnace.

15 The products of combustion which develop from such firing are passed out of the furnace in the reverse order through the ports temporarily not in use for the entrance of the heating gas 20 and into chambers partly filled with checker brick which absorb some of the sensible heat of these products and from which they are passed onward into the furnace stack. At relatively 25 short intervals these reversals are effected by shutting off the gas and air at one end of the furnace and introducing them through the checker chambers at the opposite end.

30 In passing through the checker chambers the gases absorb some of the heat stored in the checker bricks, and enter the furnace with a high sensible heat, consequently producing a much higher temperature of combustion than 35 can be obtained without preheating which is essential in order to provide the temperatures required for the production of open-hearth steel. In accordance with the usual practice, the reversals are effected at intervals of from fifteen to thirty minutes and are repeated until the oxidation of the charge has reached a desired point.

35 Among the disadvantages of such prior practice is the deleterious effect upon the steel of the constantly varying temperatures resulting from 40 the periodical reversing of the firing. In addition considerable time and heat are wasted during the reversing operations. This is due to the reversals taking several minutes, and to the fact that the gases contained in the checker chambers and uptakes at the time of the reversing of

the firing in each direction are passed out of the stack without reaching the furnace.

45 A further disadvantage is that duplicate air and fuel supplying apparatus in the way of burner ports and reversing valves are required 5 at the end of the combustion chamber and also corresponding duplicate sets of regenerators and reversing valves in the exhaust passages. Such duplication of parts materially adds to the initial cost of the furnace and due thereto and to the 10 uneven heating conditions encountered together with the complicated problems resulting from the reversing operations, the maintenance of the furnace is made very costly. In addition considerable valuable time as well as heat is lost 15 when repairs are required, which is relatively frequently, and, as will be appreciated, this all adds to the cost of the steel.

20 With these and various other difficulties in mind it is an object of this invention to provide an improved method of producing open-hearth steel in accordance with which the steel is subjected to uniform or selectively regulated heating, whereby a considerable saving of time and operating cost as well as improvement in the 25 product is effected.

25 Another object is to provide a furnace for practicing this method in which there is no unnecessary duplication of parts and in which the heating is carried out in a continuous uninterrupted process. This greatly reduces the initial 30 cost of the furnace and due to the uniformity of the heating the maintenance cost is likewise reduced.

35 Another object is to increase the life of the furnace as well as increase its output over that of a furnace of the prior type having an equivalent size.

40 A further object is to provide an improved and novel as well as practical uni-directional method of firing an open-hearth furnace.

45 These and various other objects as well as the various other novel features and advantages of the invention will be apparent when the following detailed description is read in conjunction with the accompanying drawings of which Fig. 1 is a plan view of a furnace designed to practice this invention; Fig. 2 a vertical section taken on the line II—II of Fig. 1 showing in addition certain optional features which may be 50 utilized; Fig. 3 a vertical section taken on the line III—III of Fig. 1; Fig. 4 a vertical section taken on the line IV—IV of Fig. 1; Fig. 5 a horizontal section taken on the lines V—V of Figs. 3 and 4; Fig. 6 a vertical section taken on the line 55

VI—VI of Fig. 1; Fig. 7 a vertical section taken on the line VII—VII of Fig. 1; Fig. 8 a vertical section taken on the line VIII—VIII of Fig. 7; Figs. 9 and 10 horizontal and vertical sections, respectively, of a firing end for the furnace adapted for use with natural or coke-oven gas, tar or oil; and Figs. 11 and 12 views similar to Figs 9 and 10 of an end construction adapted for use with producer gas, blast furnace gas or a mixture of gases such as blast furnace and coke-oven gas, etc.

In accordance with the invention a furnace is provided in which one-way firing is employed and with which recuperators are used for heating the air or air and fuel burned in the furnace, the furnace being designed at its firing end to provide a burner adapted to thoroughly mix the fuel and air without regard to the customary necessary dimensions for exhaust gases which in the past has militated seriously against proper and efficient firing. The other end of the furnace in turn is equipped with a suitable outlet for conducting the products of combustion into a slag pocket or chamber in which the solids carried by such products from the combustion chamber are permitted to collect and from whence the gas is discharged into the recuperators free of such ingredients.

In practicing the invention the furnace is first lighted and brought up to charging temperature, during which period the recuperators through which the fuel and air flow oppositely to the products of combustion are gradually elevated in temperature. When a proper temperature for charging is provided the charge is placed in the furnace and subjected to a continuous uninterrupted uniform heat until its oxidation is complete. The melt is then taken from the furnace in any suitable manner.

Referring in detail to the drawings by way of illustration, the numeral 1 designates generally the furnace proper in which there is provided a common form of hearth 2 having charging doors 3 arranged adjacent its sides in the walls of the furnace for the admission of scrap, pig iron, etc., comprising the charge. A tap-hole 4 is also provided by means of which the melt is removed after the oxidation or heat treatment of the charge is completed.

To reiterate, according to the invention the furnace is fired from one end only, being equipped for that purpose at its firing end with an accurately and efficiently designed main burner port 5 and an auxiliary burner port 6. The main burner port is adapted to supply most of the fuel and air utilized in the furnace and is preferably placed as low as possible in order to sweep the hearth and sinter the materials in preparing the hearth for the charge. The auxiliary ports 6, which may be eliminated if not required, or increased in number if desired, depending upon the size of the furnace, are mounted on the roof 7 and preferably at a steep angle so as to direct their supply of fuel and air at high velocity toward the metal contained in the hearth in a fashion to maintain a uniform temperature throughout the furnace.

The roof 7 which constitutes the top of the combustion chamber 10 may be plain or arched and made out of any suitable refractory material. For support it is suspended from a series of cross-beams 8 which are covered over with sheet steel or other suitable material in such a manner as to provide a cooling chamber 9 extending over the entire roof of the combustion

chamber. To permit a flow of cooling air to be circulated through such chamber to cool both the roof and its supporting structure, openings 11 and 12 are provided at opposite ends of the furnace, and a vent or connection 13 is located 5 on the top thereof for connecting it to any suitable suction device capable of providing the proper circulation.

Back of the hearth 2 there is provided a down-draft passage 14 through which the products of combustion are conducted from the combustion chamber 10 into a slag pocket or chamber 16. This chamber is adapted to collect the solids carried out of the combustion chamber by the hot gases, and from it such gases, free 15 of the ingredients, are passed into a series of recuperators 17, 18 and 19 which are employed to recover the waste heat from such products and to utilize it in preheating the air delivered to the combustion chamber by the burner ports 20 5 and 6.

The first of these recuperators consists of a substantial rectangular housing 21 constructed of suitable refractory material such as fireclay brick properly reinforced with steel buckstays 25 (not shown). Communicating with the wall of this housing adjacent the furnace in the upper mid-section thereof is a duct or tunnel 26 leading from the slag pocket 16. Opposite the inlet of this duct as shown in details in Figs. 3, 30 5, 6, 7 and 8 there is provided a series of honeycomb-like walls 20 formed of somewhat spool-shape fire-proof tile or blocks 22 which are supported by a transverse wall 23 located above the base of the recuperator, and extended to a 35 second transverse wall 30 spaced from the roof of the recuperator.

As shown in Figs. 7 and 8 the blocks comprising these intermediary vertically disposed honeycomb-like walls 20 consist of a pair of 40 square laterally spaced flat end walls 22a connected together by tubular center sections 22b, said square end sections being provided with suitable interlocking means (not shown) for rigidly effecting their assembly in the form of 45 a wall. As illustrated these walls form a series of channels 24 opening into the inlet 26 and through which the waste products are passed into an outlet duct or tunnel 43 connecting this recuperator with the next recuperator 18, and 50 as will be appreciated by reason of the tubular sections in the blocks 22 these gases are permitted to pass freely between such channels 24.

Connected to the chamber 80 formed in the recuperator below the transverse flow block supporting wall 23 is an air duct 42 by which the outlet of recuperator 18 is connected to this recuperator and from this chamber the air is passed upwardly through openings 25 in the wall 23 between the end sections 22a of the blocks 60 22 and about the tubular sections 22b into a chamber 70 formed by the transverse wall 30 and the top of the recuperator.

In the next recuperator 18 a series of four walls 31, 32, 33 and 34 is arranged between the 65 ends of the outer housing thereof to provide up and down-draft passages 35 and 36, respectively, for the products of combustion and chambers 31 and 38 for the air. As shown best in Figs. 4, 5 and 6 the outlet gas passage 27 of recuperator 70 17 is connected to the bottom of the up-draft passage 35. To provide a definite path for the waste gas from this up-draft passage 35 to the down-draft passage 36 the middle section 39 of the roof of the recuperator is raised and the 75

upper ends of the walls 32 and 33 are joined by a covered wall 40.

For passing the air through this intermediate recuperator from its air chamber 37 which is connected by a conduit or tunnel 41 with the outlet of the last recuperator 19 and the chamber 38 which is connected by a tunnel 42 with the inlet chamber 86 of recuperator 17, a series of tiers of tubes 44, and 44a is mounted in the walls 31, 32, 33 and 34, respectively, and to facilitate the mounting of these tubes as well as for cleaning them, the walls 32 and 33 in the center of the recuperator 18 are spaced sufficiently far apart to form a chamber 40a in which a man may work. It is also contemplated that suitable baffling (not shown) may be inserted in the various recuperators to channel the gas through them in such a way as to bring about efficient transfer of the heat from the exit gases to the preheated air for combustion. Furthermore, while tubes are shown in the recuperators for conducting the air through them, any type or shape of passage may be used so long as mixing of the exhaust gas and air is not permitted.

From the lower end of the down-draft passage 36 in the recuperator 18 a flue tunnel 50 is connected to the bottom of the recuperator 19 and through it the waste gases are passed upwardly between vertically disposed walls 45 to an outlet flue 46, horizontal baffles 47 being arranged between the walls 45 to provide a more circuitous path for the incoming air.

To provide a fixed draft for the furnace the flue 46 is connected to the inlet of a fan 48 which is operated by a motor 49 and has its outlet in turn connected by a flue 51 to a stack 51a, and for installations where it is non-essential to pass all of the products of combustion through this recuperator, a by-pass stack connection 100 is connected directly from the tunnel 50 to the stack 51a, being provided with a damper 101 for controlling the amount of gases passed through it. As illustrated best in Fig. 5 the walls 45 are mounted in pairs and these pairs are spaced from each other to provide passages 52 for the passage of the air through the recuperator, the lower ends of the latter passages being arranged to communicate with tunnel 41 leading to the air inlet of recuperator 18 and their upper ends with a conduit 53 which is connected to the outlet of an air drafting fan 54 which is operated by a motor 55. As shown, to take advantage of the heat absorbed by the air passed through the cooling chamber 9 over the roof of the furnace, and also to make use of the air drafting fan for cooling the roof as well as supplying air to the combustion chamber in the furnace, the inlet of the fan 54 is connected to the vent 13 in the top of the furnace by a conduit 56 having a drafting damper 57 in it. For communicating the air supplied by the fan 54 as it leaves the outlet chamber 70 of recuperator 17 to the burner ports 5 and 6, conduit or tunnel 58 is utilized.

In the operation of the furnace the products of combustion are drawn from the combustion chamber 10 by the drafting fan 48 through the recuperators 17, 18 and 19 in the path marked by the double-headed arrows in the drawings, which is traced from chamber 10 through the passage 14 into the slag pocket 16, thence by passage 26 into the upper wall of the recuperator 17 through which it is forced downwardly through the channels 24 and the tubular sections 22a of the baffle blocks 22 into the down-draft

passage 27 which carries it into the bottom of the up-draft passage 35 and the recuperator 18. In this passage it passes by the tube 44a, the down-draft passage 36, around the tubes 44 and by way of the passage or flue 50 into the bottom 5 of recuperator 19 from whence it passes upwardly between the walls 45 into the flue 46 and then by way of the fan 48 into the flue 51 which carries it to the furnace stack and the atmosphere.

The air in turn is forced by fan 54 through recuperator 19 by way of passage 52 into the chamber 37 of recuperator 18 from whence it passes through the tubes 44 and 44a into chamber 38 and from there by passage 42 into the 15 chamber 60 of recuperator 17. From this chamber it passes through the channels 25 defined by the walls 20 into the chamber 10 and from thence by way of duct 58 to the burner ports 5 and 6.

As shown in Fig. 2, fuel is fed into the furnace by a passage 61 which has branches 62 and 63 running to the main and auxiliary ports 5 and 6. However, as shown in Figs. 9, 10, 11 and 12, the burner end of the furnace may be differently 25 constructed as required for handling different kinds of fuel.

In Figs. 9 and 10, a form of burner construction is illustrated for use with coal tar, oils, natural gas and oils, while in Figs. 11 and 12 a 30 type of furnace construction is shown for use with natural gas, coke oven gas, producer gas, blast furnace gas, mixed gas and the like. In the latter, inlet 61a is particularly adapted for producer gas.

As will be appreciated by those skilled in the art, the tubular blocks 22 employed in the first recuperator 17 are made of some suitable refractory material such as chrome or mullite which will not be deleteriously affected by the products of combustion or the impurities in the form of oxides or slags which they carry.

It will also be appreciated, however, that it is very difficult in view of the great temperatures and great changes in temperature encountered 45 by such recuperators to maintain a sealed contact between the blocks 22 because of the considerable expansion and contraction which will take place between them. Nevertheless it is most desirable in this construction to prevent 50 any intermingling of the air and the products of combustion. Ordinarily in most recuperators this is aggravated by reason of the fact that the air is passed therethrough at a pressure higher than atmosphere while the waste gases are 55 passed through at a pressure below atmosphere, which in a construction of this type would normally tend to produce a considerable leakage of the air into the waste gas products through the joints which develop between the 60 recuperator blocks as a result of the cracks formed by expansion and contraction.

To eliminate this condition, or in other words balance these pressures, an auxiliary fan 102 is provided which is equipped with a motor 103 and 65 arranged with its inlet connected by a duct 104 with the air passage 42 connecting the recuperator 18 to the recuperator 17, and its outlet 104a connected to a duct 105 which is projected into the tunnels 58 in a manner to function as a jet 70 tending to increase the suction on the air passing through the recuperator 17, this arrangement being utilized to balance the pressure of the air and waste products in the recuperator.

To automatically maintain a balance of such 75

pressures, a regulator 107 is provided, being any one of a number of well-known constructions of this character and connected by suitable tubes 108 and 109 with the channels 25 between the top and bottom of the recuperators and the channels 24 defined by the walls 20. This regulator, as will be readily appreciated without necessarily describing the details thereof, is connected to suitable control means 106 connected to the supply circuit 110 of the fan motor 103 to so regulate the operation of the fan 102 as to maintain the desired air pressure in the recuperator.

It will also be appreciated that by reason of the passages 24 in the recuperator 17 being made relatively large as illustrated, they provide an unobstructed and free passage permitting a slow movement of the gas in a general downward direction so that the gases effectively give up their heat by radiation to the outer walls of the blocks 22 as well as to the surface of the tubular sections 22b which are in direct contact with the air passing upward and around them and the channels formed between them and sections 22a. Such construction also militates against any clogging of the recuperator by reason of any deposit which may not settle out of the waste products in the slag pockets settling in such channels.

In the second recuperator 18, due to the temperature of the gases being somewhat reduced by the time they reach the tubes 44 and 44a, the latter may be made of different material than that used in the formation of blocks 22 in the recuperator 17, and preferably a material such as carborundum which has a higher coefficient of conductivity than mullite or chrome, while in recuperator 19 metal may be used to form the air and gas passage. Such metal will suffice for the construction and is preferably used because of its high heat conducting qualities.

To provide a maximum efficiency for the recuperators and a minimum cost, the cross-section of the air and gas passages is reduced from the first to the last recuperator in accordance with the variations in the volume of the gas and air passing through them which vary as their temperatures. In their construction, consideration is also given to the control over the speed of passage of the air and gas through them to afford the maximum transfer of heat.

To provide for forcing air into the roof-cooling chamber 9 for cooling purposes only a separate fan 81 disposed to be operated by a motor 82 may be mounted with its outlet connected by a conduit 83 with the duct 56, a gate 84 being provided in the duct 83 for disconnecting it from the duct 56 when the fan 54 is used.

To permit the operation of the fan 54 when the fan 81 is operated, a shut-off gate 85 may be provided in duct 56 on the draft fan side of the duct 83, and an outlet gate 86 may be provided opposite thereto in duct 56 for letting the inlet air enter the duct 56 ahead of the regulating valve 57. When the fan 81 is operated the openings 11 and 12 are closed so that the cool air forced in the chamber 9 will be forced through the interstices between the brickwork of the furnace roof and not only cool the roof but also provide a shield on the underside of the roof to protect the roof against the products of combustion in the combustion chamber. As further precaution against injury to the roof from overheating, ventilator 71 may be present in the

roof and doors 72 provided in the sides of the chamber 9 and adapted to be opened to permit gravity circulation of cooling air through the cooling chamber in case of a cooling fan failure.

In the manufacture of open-hearth steel through the use of a furnace having the foregoing characteristics it will be appreciated that the charge during the process of oxidation is subjected to a continuous and substantially uniform heat. Consequently, its properties can be more accurately regulated and its quality by reason thereof improved as well as its volume from a given quantity of charge considerably increased. In addition, its cost of production is materially reduced by reason of the fact that the overhead cost incidental to the installation and maintenance of the furnace is materially reduced as well as the fact that the time required for reducing a charge to the proper constituents is greatly lessened inasmuch as the intermittent time losses due to varying reversals are eliminated.

In addition, among the detailed advantages of the invention is the saving in cost effected by the elimination of reversing valves, duplicate burners, double air regenerators and the like. Another is the saving in maintenance possible because of the longer life which the furnace enjoys due to the uniform heating conditions under which it operates. A further advantage is the greater economy obtained by means of the greater heat efficiency flow from the unidirectional firing. In addition, there are numerous other advantages which will be apparent to those skilled in the art.

While the furnace as illustrated and described constitutes an embodiment of the invention intended more particularly for refining steel, it will be understood that the invention may be applied to other processes where high temperatures are required, such as in the melting of glass and the like.

According to the provisions of the patent statutes, I have explained the principle and mode of operation of my invention and have illustrated and described what I now consider to represent its best embodiment. However, I desire to have it understood that within the scope of the appended claims the invention may be practiced otherwise than as specifically illustrated and described.

I claim:

1. An open hearth furnace comprising a melting hearth forming the bottom wall of an enclosed heating chamber, heating means at one end of the chamber above the hearth embodying fuel and air supply means, means for withdrawing the products of combustion at another end of said chamber, and means for preheating the air supply to the heating means by the heat of the products of combustion leaving the heating chamber including means for balancing the pressure of the preheated air entering the furnace and the products of combustion or waste gases leaving the furnace chamber, said pressure balancing means being responsive to and controlled by variations in the pressure of the waste gases or products of combustion leaving the furnace chamber and the preheated air entering said chamber.

2. In an open hearth furnace, the combination with a melting chamber of a recuperator structure having waste gas and preheated air passages leading to said chamber, said passages being in heat exchange relation, means for con-

ducting waste gases and air under pressure through said recuperator passages, and means responsive to the pressure differential of the fluids in said recuperator passages for changing the pressure of the air to substantially the same pressure as the waste gases.

5 3. An industrial heating furnace comprising a heating chamber, heating means at one end of the chamber above the hearth embodying fuel and air supply means, a waste gas passage for withdrawing the products of combustion at another end of said chamber, a recuperator communicating with said waste gas passage and with the air supply means and embodying heat exchange passages for the waste gases and air to be preheated, means for maintaining constant pressure of the air in said heat exchange passages, and means for increasing the volume of air delivered to the heating chamber independently of said pressure controlling means.

10 4. An industrial heating furnace comprising a heating chamber, heating means at one end of the chamber above the hearth embodying fuel and air supply means, a waste gas passage for withdrawing the products of combustion at another end of said chamber, a recuperator communicating with said waste gas passage and with the air supply means and embodying heat exchange passages for the waste gases and air to be preheated, a pressure regulator operative in response to variations in the pressure of the gases, and air passing through said heat exchange passages for maintaining a predetermined relation of the pressure in the waste gas and air passages.

15 5. An industrial heating furnace comprising a heating chamber, heating means at one end of the chamber above the hearth embodying fuel and air supply means, a waste gas passage for withdrawing the products of combustion at another end of said chamber, a recuperator communicating with said waste gas passage and with the air supply means and embodying heat exchange passages for the waste gases and air to be preheated, air pressure means connected to the air passages of the recuperator and also directly to the air passage leading to the heating chamber, and pressure regulating means for automatically regulating the air pressure means to vary the volumes of air delivered to the air passages of the recuperator and the air passage of the furnace chamber.

20 6. An industrial heating furnace comprising a heating chamber, heating means at one end of the chamber above the hearth embodying fuel and air supply means, a waste gas passage for withdrawing the products of combustion at one end of said chamber, a recuperator communicating with said waste gas passage having heat exchange passages for the waste gas and air supplied to the furnace chamber, a blower connected to the recuperator to supply air to the heat exchange passages, a motor for said blower, a regulator responsive to the waste gas pressures and air pressures in the heat exchange passages of the recuperator, said regulator having control means connected to the motor to regulate the speed of the motor in accordance with the pressure differential of the gases and air in the heat exchange passages.

25 7. In an industrial heating furnace, a heating chamber, heating means comprising a plurality of burners, fuel supply means therefor, air passages for delivering air to the burners to support combustion in the heating chamber, a waste gas

30 passage for drawing the products of combustion from the furnace chamber, a primary refractory recuperator having heat exchange passages communicating with the waste gas and air delivering passages of the furnace, a secondary metallic recuperator having heat exchange passages in communication with the heat exchange passages of the first recuperator, means for delivering air under pressure to and from the secondary recuperator to the primary recuperator, means for exhausting the waste gases from the furnace chamber through said recuperators in the order mentioned, and means for supplying additional air to the first recuperator in accordance with a desired volume and pressure of the air passing through the heat exchange passages to the furnace chamber.

35 8. In an industrial heating furnace, a heating chamber, heating means comprising a plurality of burners, fuel supply means therefor, air passages for delivering air to the burners to support combustion in the heating chamber, a waste gas passage for drawing the products of combustion from the furnace chamber, a primary refractory recuperator having heat exchange passages communicating with the waste gas and air delivering passages of the furnace, a secondary metallic recuperator having heat exchange passages in communication with the heat exchange passages of the first recuperator, means for delivering air under pressure to and from the metallic recuperator to the primary recuperator, means for exhausting the waste gases from the furnace chamber through the primary and secondary recuperators in the order mentioned, and means for supplying additional air to the heat exchange passages of the primary recuperator and to the air passage leading from the recuperator to the furnace chamber.

40 9. In an industrial heating furnace, a heating chamber, heating means comprising a plurality of burners, fuel supply means therefor, air passages for delivering air to the burners to support combustion in the heating chamber, a waste gas passage for drawing the products of combustion from the furnace chamber, a primary refractory recuperator having heat exchange passages communicating with the waste gas and air delivering passages of the furnace, a secondary metallic recuperator having heat exchange passages in communication with the heat exchange passages of the first recuperator, means for delivering air under pressure to and from the metallic recuperator to the primary recuperator, means for exhausting the waste gases from the furnace chamber through the primary and secondary recuperators in the order mentioned, and means for balancing the pressure of the air and waste gases in the heat exchange passages of the first-named recuperator.

45 10. In an open hearth furnace, a heating chamber, fuel burners and preheat air passages for said chamber, a waste gas passage leading from said chamber, a cooling chamber above the furnace, exhaust means for said cooling chamber, a plurality of recuperators having heat exchange passages for successively receiving the waste gases from the furnace chamber and delivering preheated air to support combustion in said chamber, and means for drawing air through the cooling chamber above the furnace and delivering it to the recuperators.

50 11. In an open hearth furnace, a heating chamber, fuel burners and preheat air passages for said chamber, a waste gas passage leading

for said chamber, a waste gas passage leading from said chamber, a cooling chamber above the furnace, exhaust means for said cooling chamber, a plurality of recuperators having heat exchange passages for successively receiving the waste gases from the furnace chamber and delivering preheated air to support combustion in said chamber, means for drawing air through the cooling chamber above the furnace and delivering it to the recuperators, and means for supplementing the air supply after it has passed from the recuperators.

12. In an open hearth furnace, a heating chamber, fuel burners and preheat air passages

from said chamber, a cooling chamber above the furnace, exhaust means for said cooling chamber, a plurality of recuperators having heat exchange passages for successively receiving the waste gases from the furnace chamber and delivering preheated air to support combustion in said chamber, means for drawing air through the cooling chamber above the furnace and delivering it to the recuperators, and means for supplementing the air supply to the recuperators 10 and to the preheated air passage leading to the furnace chamber. 5

MARTIN J. CONWAY.
